UNITED STATES PATENT OFFICE

2,680,165

EMERGENCY CONTROL ACTUATOR

Oscar H. Hasselbaum, Arlington, Mass., assignor
to Joseph Pollak Corporation, Dorchester,
Mass., a corporation of Massachusetts

Application April 2, 1952, Serial No. 280,092

7 Claims. (Cl. 200—18)

1

The present invention relates to an emergency control device for operating a plurality of switches simultaneously in the imminence of a crash or other sudden occurring event wherein safety demands that action be immediately taken to turn off the sources which might cause fire or explosions.

The device of the present invention is used more particularly in the operation of air crafts for simultaneously turning off a number of master switches to shut off the engine, motors and power sources and other operating devices.

The device of the present invention will be installed on a panel switch-board for operating a plurality of switches from "on" to "off" positions.

A feature of the present invention is that the actuator device cannot be accidentally operated in either direction and therefore it is impossible to turn off the switches accidentally as when somebody may come against the actuator. Positive and intentional operation is required for the actuator of the present invention.

A further feature of the present invention is that it is simple in construction, that it will withstand considerable abuse, that it has certain flexible parts which will not allow the device to become jammed in any way and that it requires for operation a simple coordinated movement which can be accomplished extremely rapidly.

Without further describing the merits and advantages of the present invention, the invention will be described in connection with the drawings illustrating an embodiment of the same, in which:

Figure 1 shows an elevation of the invention as applied to a plurality of similar switches mounted on the panel board.

Figure 2 shows a plan view looking upward from the bottom of Fig. 1.

Figure 3 shows an end view looking from the right of Figure 2.

Figure 4 shows a section taken on the line 4—4 of Figure 1, and,

Figure 5 shows an end view of Figure 1 with the switches mounted on the switch panel and the actuator positioned in relation to them.

In the arrangement indicated in the drawings, the switch panel 1 has a plurality of switch housings 2, 2, etc., mounted therein, each of which has an operating switch arm 3 projecting forward from the switches which have pins or arms 4 positioned to engage the actuator arms 5, 5, 5, 5, under conditions which will presently be described.

The switch arms 3 are shown as pivoted arms

5 pivoted in the switch housing with the pins or arms 4 extending from the rear of the switch elements for engaging the actuators 5 which are in a plane spaced a short distance, perhaps $\frac{1}{4}$ " from the front plate or cover 6 of the switch housing. The actuator system of the present invention will operate not only for a plurality of pivoted switch arms, but will also operate for switch arms which may move in laterally or non-arcuate movement, and in fact the actuator may be applied to a combination of different operating types of switches as will readily be seen from the description below.

10 The actuator of the present invention comprises a housing 8, which as indicated in Figure 4 has an inverted U-shaped shell 9 with a downwardly extending flange 10 (see Figures 1 and 4) and a cover plate 7 covering the open end of the U-shaped section with an extending flange 11 facing the flange 10. The end cap 12 covers the end of the U-shaped shell. This cap has a flange 13 which is faced over the cover plate 7 and riveted to it by rivet 14 thus closing the end of the shell or housing. The U-shaped housing extends over the whole length of the device and is slotted at spaced intervals at the top by slots 15, 15, etc., to permit the actuator arms 5 to extend through the housing. Within the housing the actuator arms are supported by short rods or shafts 16 which have a sliding fit within the housing from which the arms 5 extend laterally or what might be considered radially from the shaft. These shafts 16 are internally bored and threaded to receive a flexible screw cable 17, which extends through all of the shafts from the one at the end to which the actuator arm is attached to the one at the end in which it terminates in an end cavity. At the other end of the shaft 16, the bore or cavity 17 contains right 20 the end of a coiled spring 18, the other end of which abuts against the end plate 12. The shaft 16 may be properly positioned along slots 15 at the desired places. All of the arms 5 extending from the housing 8 are operated simultaneously. This is accomplished through the single arm or bar 19 extending from one of the shafts 16, outwardly through a slot in the lower side of the housing 8. This bar 19 has an end 20 (see Figure 2), which projects into the base of a slidable plate 21 mounted on a flange plate 22 which is riveted or clamped over the plate 10 as shown in Figure 1 by nuts and bolts 23 which pass through the flange 10 and also the individual switch plates and panel boards. The sliding plate 21 is constructed with arms 24 and 25

extending lengthwise on either side of an operating handle 26. These arms 24 and 25 are provided with bolt and nut elements 27 and 28 respectively, the bolts of which pass through slots 29 and 30 respectively, which limit the sliding motion of the plate. In juxtaposition to the handle 26 is a trigger handle 31 which is pivoted at 32 in an ear 33 of the supporting plate 21. The trigger handle 31 is formed as a lever with a forked end 34 beyond the pivot 32, which forked end surrounds the head 35 of a stud 36. The stud 36 works up and down in a cup 37 formed in the plate 21. In this cup there is positioned a coil spring 38 which surrounds the stud 36 and which is compressed by a pin or plate 39 attached near the lower end of the stud 36 so that when the trigger 31 is moved towards the handle 26, the stud or pin 36 will be raised to compress the spring and the end of the stud 36 will thereby be moved out of the hole 48 in the supporting flange or base 22. When the pin 36 is raised in this fashion the handle 26 as viewed in Figure 2 may be moved to the right for the length of the slots 29 and 30. This motion will simultaneously move all the arms 5 and restore all the switch arms 3 to their inoperative positions. At the same time that this takes place, the spring 18 in the housing 9 will be compressed and when the arm 26 is released all the actuator arms, the shaft 16 and the arm 26 will be returned to the left to their initial position and the pin or stud 36 will reset itself in the hole 40. This action turns off all the switches simultaneously in definite and positive motion. In event that anything has happened to disalign the housing or shell, the actuator may still be operated. The motion required for operation is simply that of squeezing the trigger and handle 26 together and moving the handle to the right as viewed in Figures 1 and 2.

In the construction as shown in Figure 5, the actuator assembly is mounted with the same mounting nut and bolt assembly 23 as that used for mounting the individual switches on the panels so that the proper positioning of the actuator arm is assured for the assembly by the location and mounting holes of the actuator arm assembly in the panel board.

Having now described my invention, I claim:

1. An actuator for a plurality of switches, each having independent switch handles operated by said actuator comprising a plurality of actuator arms positioned each in proximity to one of said switch handles, a manual actuator member connected to said actuator arms, means mounting said member for permitting it to be moved in one direction to actuate said switch handles, a locking member having a manual operating means positioned adjacent said manual actuator member for restraining the operation of said manual actuator member and operative with the latter in the opposite direction from the operation of the manual actuator means.

2. An actuator for a plurality of switches, each having independent switch handles operated by said actuator comprising a plurality of actuator arms positioned each in proximity to one of said switch handles, a manual actuator member connected to said actuator arms, means mounting said member for permitting it to be moved in one direction to actuate said switch handles, and means operative towards said member for releasing said first means for the initial operation thereof.

3. An actuator for a plurality of switches, each

having independent switch handles operated by said actuator comprising a plurality of actuator arms positioned each in proximity to one of said switch handles, a manual actuator member connected to said actuator arms, means mounting said member for permitting it to be moved in one direction to actuate said switch handles, and means operative towards said member for releasing said first means for the operation thereof, including a trigger grip adapted to be squeezed towards said member for releasing said first means for the operation thereof.

4. An actuator for a plurality of switches each having independent switch handles operated by said actuator comprising a plurality of shaft elements each having an actuator arm extending from the side thereof positioned in proximity to one of said switches, a flexible cable member joining in alignment all of said shaft elements whereby they all move longitudinally one with the other, a shell acting as a sleeve for said shaft elements and said cable, a spring within said shell adapted to be compressed by said longitudinal movement, means for manually moving said actuators in the direction to compress said spring and means adapted to be released for permitting said manual movement.

5. An actuator for a plurality of switches each having independent switch handles operated by said actuator comprising a plurality of shaft elements each having an actuator arm extending from the side thereof positioned in proximity to one of said switches, a flexible cable member joining in alignment all of said shaft elements whereby they all move longitudinally one with the other, a shell acting as a sleeve for said shaft elements and said cable, spring means acting at one end of said shaft elements and adapted to be energized by the movement of said shaft elements in one direction, means for manually moving said actuators in said direction and means adapted to be released for permitting said manual movement.

6. An actuator for a plurality of switches each having independent switch handles operated by said actuator comprising a plurality of shaft elements each having an actuator arm extending from the side thereof positioned in proximity to one of said switches, a flexible cable member joining in alignment all of said shaft elements whereby they all move longitudinally one with the other, a shell acting as a sleeve for said shaft elements and said cable, one of said shaft elements having an operating arm projecting outwardly from said shaft at a different angle from its actuating arm, an operating handle mounted in a free support connected to said operating arm, a latch mechanism normally retaining the operating handle in a fixed position having an operating trigger adjacent said handle for releasing the operating handle whereby the trigger may be squeezed in the same motion with the movement of the operating handle for actuating said actuator arms.

7. An actuator for a plurality of switches each having independent switch handles operated by said actuator comprising a plurality of shaft elements each having an actuator arm extending from the side thereof positioned in proximity to one of said switches, a flexible cable member joining in alignment all of said shaft elements whereby they all move longitudinally one with the other, a shell acting as a sleeve for said shaft elements and said cable, one of said shaft elements having an operating arm projecting out-

wardly from said shaft at a different angle from its actuating arm, an operating handle mounted in a sliding bearing parallel to said shafts and flexible cable members, a trigger latch positioned adjacent said handle normally maintaining said handle immovable and released upon pressing for motion of the operating handle in the opposite direction from that of pressing the trigger.
